CLAIM

The ornamental design for a motorcycle frame tail, as shown and described.

DESCRIPTION

FIG. 1 is a top, left, front perspective view of a motorcycle frame tail showing our new design;

FIG. 2 is a bottom, right, rear perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a bottom plan view thereof; and,

FIG. 8 is a top plan view thereof.

The broken line indicated by dashes showing in FIGS. 1-8 is for the purpose of illustrating portions of the motorcycle frame tail and forms no part of the claimed design. The distinct broken line indicated by alternating dashes and dots showing in FIGS. 1-8 is for the purpose of illustrating a boundary line between claimed and unclaimed portions of the design and forms no part of the claimed design.
